UNITED STATES PATENT OFFICE.

HENRI JEAN BAPTISTE GRAVIER, OF ITHACA, NEW YORK.

DESIGN FOR A SHIP-PROTECTOR.

SPECIFICATION forming part of Design No. 29,635, dated November 8, 1898.

Application filed July 29, 1898. Serial No. 687,216. Term of patent 14 years.

To all whom it may concern:

Be it known that I, HENRI JEAN BAPTISTE GRAVIER, a citizen of France, residing at Ithaca, in the county of Tompkins and State of New York, have invented and produced a certain new and original Design for Ship-Protectors; and I do declare the following to be a full, clear, and exact description of the invention, such as will enable others skilled in the art to which it appertains to make and use the same.

The invention has relation to a new and original design for ship-protectors; and it consists of a protector of the configuration shown in the accompanying drawings, in which—

Figure 1 is a front view. Fig. 2 is a side elevation, and Fig. 3 is a cross-sectional view.

The leading features of my design consist of a longitudinal body provided with diverging wings 2, between which is formed a groove 3. The lower end of the longitudinal body portion is curved inwardly, as at 4, and the sides of the body portion are provided with holes 5.

What I claim is—

The design for a ship-protector as herein shown and described.

In testimony whereof I have hereunto set my hand in presence of two subscribing witnesses.

HENRI JEAN BAPTISTE GRAVIER.
